Primary Examiner — Eric L Goodman*Assistant Examiner* — Sarah L Smith(74) *Attorney, Agent, or Firm* — Tarter Krinsky & Drogin LLP(57) **CLAIM**

The ornamental design for a tripod light, as shown and described.

DESCRIPTION

FIG. 1 is a perspective view of a tripod light in a closed configuration;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a perspective view of the tripod light in an open configuration.

The broken lines shown in the figures are environmental and form no part of the claimed design.
